TABLE

Samuel E. Adler, Chicago, Ill., assignor to Admiral Corporation, Chicago, Ill., a corporation of Delaware

Application December 6, 1954, Serial No. 33,414

Term of patent 14 years

(Cl. D33—14)

Fig. 1.

Fig. 2.

Fig. 3.

Fig. 1 is a perspective view of a table showing my new design;

Fig. 2 is a side elevational view thereof; and

Fig. 3 is an end elevational view of the same, the legs having been broken away, for convenience of illustration only.

I claim:

The ornamental design for a table, as shown and described.
